UNITED STATES PATENT OFFICE.

KONSTANTY DOMASHEWICZ, OF PHILADELPHIA, PENNSYLVANIA.

PERCUSSION MUSICAL INSTRUMENT.

Specification of Letters Patent.

Patented Nov. 16, 1915.

1,160,392.

Application filed January 13, 1915. Serial No. 1,908.

To all whom it may concern:

Be it known that I, KONSTANTY DOMASHEWICZ, a subject of the Czar of Russia, residing at Philadelphia, in the county of Philadelphia and State of Pennsylvania, have invented certain new and useful Improvements in Percussion Musical Instruments, of which the following is a specification.

10 My invention relates to improvements in percussion musical instruments, the object of the invention being to provide a musical instrument which embodies a number of separate instruments all operated by the feet, and particularly designed for accompanying an instrument held or played by the hands, so that the performer can play upon one instrument and accompany himself by means of the orchestra.

20 A further object is to provide a musical instrument of the character described which is inclosed within a box, and may be readily transported from place to place.

With these and other objects in view, the 25 invention consists in certain novel features of construction and combinations and arrangements of parts as will be more fully hereinafter described and pointed out in the claims.

30 In the accompanying drawings: Figure 1 is a view in front elevation illustrating my improved musical instrument in operative position. Fig. 2 is a view in horizontal transverse section on the line 2—2 of Fig. 1.

35 Fig. 3 is a view in vertical transverse section on the line 3—3 of Fig. 1. Fig. 4 is a fragmentary view in section on an enlarged scale on the line 4—4 of Fig. 2. Fig. 5 is a view similar to Fig. 4, taken on the line 40 5—5 of Fig. 2. Fig. 6 is a similar view on the line 6—6 of Fig. 2, and Fig. 7 is a similar view on the line 7—7 of Fig. 2.

1 represents a box of general oblong rectangular shape having one side 2 connected by hinges 3 to the bottom 4 of the box 1, and serving the double function of a platform and a door to close the box when ever desired.

5 is a lock on the box operated by a key 50 6 to receive lugs 7 on the platform 2, and securely lock the latter in its closed position.

8 represents a handle on the box 1 to facilitate its transportation from place to place.

55 In the box 1, a vertically positioned sounding board 9 is located, and is provided

with a central opening 10 and with an end opening 11.

12 represents a hitch plate secured to the sounding board and having screws 13 thereon for the attachment of strings 14. These strings 14 are variously arranged to provide notes or chords as the case may be. I have illustrated four sets of these strings extending longitudinally of the sounding board across the opening 10, and thence through the opening 11 to tuning pins 15 on a wrest plank 16 located in the end of the box.

17 is a hinged door located in the end of the box, and which may be opened to expose the tuning pins 15 to permit the tuning of the instrument.

For each set of wires 14, I provide a hammer 18. These hammers 18 are pivotally supported in recessed blocks 19, and at their lower pivoted ends are provided with hammer butts 20 which are engaged by treadles 21. The treadles 21 are supported in a recessed block 22 secured to platform 2, and are pivotally connected to the block 22 by means of a pin 23. The treadles 21 have longitudinal slots 24 receiving the pin 23, and coiled springs 25 connect the treadles with the hammers 18. These coiled springs 25 perform the double function of turning the hammer to normal position, and also holding the treadles in their position projected under the hammer butts 20, yet allow the treadles to be drawn backwardly when it is desired to swing the platform 2 to closed position, as will be hereinafter pointed out.

The sets of wires 14 bear against frets 26 secured to sounding board 9, and said wires are provided with spring-pressed foot keys 27 to be pressed against the wires to shorten them and vary the note or chord. These foot keys 27 have springs 28 normally holding them away from the wires 14, and are provided with cushioning blocks 29 to engage the strings when pressed inwardly by the foot. The outward movement of the keys 27 is limited by flexible wires 30 connected to the lower portions of the keys and engaging vertical bars 31 between which the keys are movable.

32 and 33 represent metal tubes supported in racks 34, and having pivoted clappers 35. These clappers 35, at their free ends, are provided with set screws 36 which operate as weights to quickly return the clapper to its outward position. Each clapper is moved

by a treadle 37 connected by a flexible device 38 with the clapper, and passed over suitable idle pulleys 39 to insure a proper operation.

- 40 represents a cymbal supported on a slide 41 mounted in guides 42 on platform 2. This cymbal is engaged by a pivoted clapper 43 mounted in a bracket 44 and having a coiled spring 45 normally holding the same in elevated position.
- 10 46 is a treadle connected by a flexible device 47 with the clapper 43, and this flexible device is also passed over idle pulleys 48 to insure the proper operation.

The treadles 37 and 46 are provided with coiled springs 49 normally holding them in elevated position, and each of the treadles may have suitable designating characters if desired. This is particularly true with relation to the treadles 21, which, at their outer ends, contain letters indicating the letters or chords of the sets of strings.

The operator stands, or is seated with his feet on the platform 2, and with his hands he manipulates any instrument, accompanying himself by playing with his feet upon the several treadles. As above explained, the treadles 21 control the operation of the hammers 18 to sound the strings 14, and the treadles 37 and 46 control the clappers 35 and 43 respectively. The clappers 35 striking against the tubes 32 and 33 give a distinct bell sound, and the clapper 43 gives the loud cymbal note.

By reference particularly to Fig. 2, it will be noted that when the parts are in operative position, the treadles 21 extend across the meeting edges of the platform 2, and the bottom 4 of box 1. Also, it will be noted in Fig. 2, that when the cymbal is in operative position, it extends across the meeting edges of the platform, and the box bottom. To close the box, it is necessary to draw the treadles 21 longitudinally, and to move the cymbal away from the box, when the platform 2 can be swung up beside the box and locked. When the platform is returned to a horizontal position, the springs 25 will return the treadles 21 to normal position shown in Fig. 7, but it is necessary to manually slide the cymbal into its operative position.

While I have described what I believe to be a preferred embodiment of my invention, I would have it understood that I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A musical instrument, comprising a sounding board, strings on the sounding board, hammers located to strike the strings, and a movable part having treadles thereon

located when in one position to engage under the hammers to operate the latter, substantially as described.

2. A musical instrument, comprising a sounding board, strings on the sounding board, hammers located to strike the strings, a movable part having treadles thereon located when in one position to engage under the hammers to operate the latter, a box enclosing and supporting the sounding board, said movable part constituting the cover of the box, substantially as described.

3. A musical instrument, comprising a box, one side of said box hinged to the bottom of the box and constituting a platform when open, a sounding board in the box, strings on the sounding board, hammers supported in the box and adapted to strike the strings, and treadles supported on the platform and engaging the hammers, substantially as described.

4. A musical instrument, comprising a box, one side of said box hinged to the bottom of the box and constituting a platform when open, a sounding board in the box, strings on the sounding board, hammers supported in the box and adapted to strike the strings, said hammers having hammer butts at their lower ends, and treadles supported on the platform and engaging under the hammer butts of the hammers, substantially as described.

5. A musical instrument, comprising a box, one side of said box hinged to the bottom of the box and constituting a platform when open, a sounding board in the box, strings on the sounding board, hammers supported in the box and adapted to strike the strings, said hammers having hammer butts at their lower ends, treadles supported on the platform and engaging under the hammer butts of the hammers, said treadles having longitudinally movable pivoted connection with the platform, and springs connecting the hammers and the treadles, substantially as described.

6. A musical instrument, comprising a box, a sounding board in the box, a plurality of sets of horizontally positioned strings on the sounding board, a hammer for each set of strings, a cover hinged to the box, and treadles connected to the cover and located when the cover is in open position to operatively engage the hammers, substantially as described.

7. A musical instrument, comprising a box, hinges connecting one side of the box to the bottom of the box, whereby the side of the box may be swung to open position and constituting a platform, a sounding board in the box, strings on the sounding board, hammers supported in the box and adapted to engage the strings, a recessed block secured to the platform, treadles movable in the recesses of the block, and adapted to be pro-

jected across the meeting edges of the platform and the box bottom, and operatively engage the hammers, and springs connecting the treadles and the hammers normally holding the hammers in retracted position, and the treadles in operative connection with the hammers, substantially as described.

In testimony whereof I have signed my name to this specification in the presence of two subscribing witnesses.

KONSTANTY DOMASHEWICZ.
